(57) **CLAIM**

I claim the ornamental design for a purse protector, as shown and described.

DESCRIPTION

FIG. 1 is a front, top and side perspective view of the purse protector embodying the design of the present invention.

FIG. 2 is a front elevational view thereof, the rear elevational view being identical to the front elevational view.

FIG. 3 is a side elevational view thereof, the side opposite being identical to the side shown in FIG. 3.

FIG. 4 is a top plan view thereof; and,

FIG. 5 is a bottom plan view thereof.

1 Claim, 3 Drawing Sheets

FIG. 2

FIG. 3
